UNITED STATES PATENT OFFICE

MARGARET E. RUNSER, OF NEW YORK, N. Y.

ADJUSTABLE CURTAIN ROD

Application filed October 22, 1929. Serial No. 401,455.

This invention relates to improvements in brackets for slidably adjusting a curtain rod vertically along the side of a window frame.

One of the objects of the invention is the provision of a pair of brackets attachable to the sides of a window frame to provide companion slides, and a rod for a curtain and a rod for a drapery mounted at their ends in supports which are adjustable in the slides, whereby the curtain and drapery carried by said rods may be lowered from their uppermost position to enable a housewife or other person to easily remove the curtain or drapery, or dust the same.

Another object of the invention is the provision of an adjustable rod for supporting a curtain or drapery, which will be of simple construction and be able to sustain the weight of a drapery or curtain.

Other objects and advantages of the invention will be hereinafter specifically pointed out, or will become apparent, as the specification proceeds.

With the above indicated objects in view, the invention resides in certain novel construction and arrangement of parts, clearly described in the following specification and fully illustrated in the accompanying drawings, which latter show an embodiment of the invention as at present preferred.

In the drawings:—

Figure 1 is a view in elevation showing the device applied to a window.

Figure 2 is a detail end elevation, showing the supports in their normal raised position.

Figure 3 is a similar view showing supports in their lower position.

Figure 4 is a detail top plan view.

Figure 5 is a detail horizontal sectional view on an enlarged scale.

Figure 6 is a detail perspective view of one of the supports.

Referring to the accompanying drawings, 5 and 6 designate the right and left sides of a window. To the right side an elongated bracket 7 is attached. This bracket is in the form of a long metal strip or plate, having a guiding portion or body 8, which is bodily offset, by the angular feet 9 and 10,

through which fastening means or screws 11 are driven into the window frame side 5. This guiding portion or body is formed with a longitudinal slot 12, parallel to the side edges of said strip, and extending uninterrupted towards the end portions of the said strip.

The left side 6 of the window frame is provided with a similar bracket 13, having offset terminal feet 14 and 15, secured by the fasteners 16, and provided with a longitudinal slot 17 parallel to the side edges of said strip.

A flat metal support 18 is inserted edge-wise in the slot 12 of the bracket 7. This support is formed with an enlarged portion at its upper end which is provided with a rectangular slot 19 and outwardly of this slot and preferably nearer the upper end of the enlarger portion, is provided an additional rectangular slot 20. The lower end of the support is reduced to provide a retaining lug or finger 21, which is adapted to rest in the pocket 22 provided between the lower end of the body 8 and the adjacent face of the window frame side, to retain the support 18 in an elevated position.

In the longitudinal slot 17 of the opposite bracket a support 23 is arranged edge-wise and this support is also retained in an elevated position by means of a lug or finger 24 that is similar to finger 21.

The support 23 is provided on its upper end with an inner rectangular slot 25 and with an outer rectangular slot 26.

In the inner slot of the support 18 the outer end of the curtain rod section 27 is inserted and in the inner slot of the support 23 the outer end of companion curtain rod section 28 is inserted. The inner ends of the rod sections 27 and 28 are coupled by means of the sliding sleeve 29 in order to retain the curtain rod comprising the sections 27 and 28 coupled to the supports 18 and 23. The outer end of said sections 27 and 28 are bent at right angle 95 as shown in Figure 5. The sleeve 29 slidably couples the sections or bars 27 and 28 to each other for relative adjustment. A thumbscrew 29^a is here provided to hold the sections 27 and 28 in adjusted position, as clearly shown

in Figure 5; and a like thumb screw 29^b is provided for the sleeve or collar 32.

In the outer slots of the supports 18 and 23 the U-shaped outer ends 30^a and 31^a of the drapery rod sections 30 and 31 are inserted, so that the rod sections 30 and 31 extend forwardly of the supports 18 and 23. The inner ends of the sections 30 and 31 are coupled to each other by means of the sliding sleeve 32.

In their upper positions the supports 18 and 23 hold the sectional rods near the upper end of the window frame. By lifting the fingers on the lower ends of said supports the sectional rods may be lowered and are held in their lowered position by straight shoulders formed by recesses 33, the shoulders being received in the pockets 22 as shown in Figure 3.

The sections of the rods are adjustable on each other to make the device fit windows of various widths.

The hereinbefore described construction admits of considerable modification without departing from the invention; therefore, I do not wish to be limited to the precise arrangements shown and described, which are, as aforesaid, by way of illustration merely. In other words, the scope of protection contemplated is to be taken solely from the appended claims, interpreted as broadly as is consistent with the prior art.

I claim as new:—

1. A curtain fixture comprising elongated brackets having longitudinally arranged slots therein, supports slidably mounted in said slots and being provided with slots disposed adjacent the upper ends thereof, a finger arranged at the lower end of each of the supports and adapted to be received in pockets formed at the lower ends of the brackets for securing the supports in raised position, curtain rods having their ends arranged in the slots of the upper ends of the supports, one of said rods cooperating with the brackets for holding the supports slidably mounted in the slots, and said supports having means received in the pockets for holding the supports in lowered position.

2. A curtain fixture comprising elongated brackets, annular feet formed therewith and providing each bracket with an offset body portion having a longitudinally disposed slot formed therein, a support mounted for slideable movement in each slot, an enlarged portion formed with the upper end of each support and being provided with slots arranged out of alignment with respect to each other, curtain rods received in the slots of the enlarged portions, one of said curtain rods cooperating with the bottoms of the brackets for retaining the supports slidably associated with respect to the brackets, a finger formed on the lower end of each support and adapted to be received by the lower end of its bracket, for holding the support in an ele-

vated position, and said supports being provided with recesses arranged at the juncture with the enlarged portions therewith, and providing shoulders adapted to receive the lower ends of the brackets for holding the supports in their lowered positions.

In testimony whereof I hereby affix my signature.

MARGARET E. RUNSER.
